UNITED STATES PATENT OFFICE.

JOSEPH MCKENNA, OF FORT WAYNE, INDIANA, ASSIGNOR TO THE FORT WAYNE ROLLING MILL CORPORATION, OF FORT WAYNE, INDIANA, A CORPORATION.

FURNACE.

1,199,091.

Specification of Letters Patent. Patented Sept. 26, 1916.

Application filed April 22, 1915. Serial No. 23,034.

To all whom it may concern:

Be it known that I, JOSEPH MCKENNA, a citizen of the United States, residing at Fort Wayne, in the county of Allen and State of Indiana, have invented new and useful Improvements in Furnaces, of which the following is a specification.

The invention relates to furnaces and particularly to rolling mill furnaces wherein oil or powdered coal is used as the fuel. In all such types of furnaces it is essential that a blast of air be provided with the oil or coal and one of the troublesome features of such use of air is that it is generally cold or the temperature of the outside air and therefore tends to lower the temperature of the heating chamber as it is blown into that chamber. The temperature of the heating chamber is necessarily kept very high in rolling mill usage and any cooling agent admitted to it is accordingly objectionable. Numerous attempts have been made heretofore to heat the air before it reaches the combustion chamber of the furnace as, for example, installing the air pipe in the walls of the combustion chamber of the furnace, also in the rear end of the furnace adjacent the exhaust or smoke stack, the purpose being that the air as it is driven through the pipe installed as just described, will be warmed and thereby aid the combustion of the fuel much more effectively than when it is in the cold state. Such installations of the pipe have many objections, the pipe is inaccessible for cleaning purposes and is rapidly disintegrated and is slow to become effective for heating the supply of air and its installation in the rear end of the furnace prevents the use of the waste heat of the furnace for heating the steam boiler. It is common practice in rolling mills to make use of the waste heat of the furnaces for heating the steam boilers of the plant, and any attachment to the furnace which will interfere with or destroy the effectiveness of the waste heat for that purpose is highly objectionable and uneconomical.

The object of the invention is to provide a furnace with means for preheating the air supplied to it which shall be at all times accessible, shall have long life and interfere with no part of the furnace nor with its proper working or with the use of its waste heat, and greatly reduce the fuel consumption during initial heating of the furnace.

Another object is to provide an adjustable discharge nozzle for the fuel in order that the direction of discharge of the fuel may be changed from time to time as desired.

In the accompanying drawings I illustrate one manner in which my invention may be carried out in practice, and in which—

Figure 1 is a longitudinal sectional view of a fraction of a furnace equipped with the invention; Fig. 2 an end view of the discharge nozzle, Fig. 3 a longitudinal sectional view of the nozzle; Fig. 4 a sectional view on line 4—4 of Fig. 1, and Fig. 5 a plan view of the head of the furnace.

Referring to the drawings, the furnace illustrated is intended for use with powdered coal as the fuel, the only change necessary, when oil is used, being that of providing a suitable nozzle for the discharge of the oil.

The combustion chamber 10 of the furnace is provided by the brick side walls 11, arched top 12, grate bars 13, vertical cross wall 14 and front wall 15. The usual coke breeze 16 is provided on the grate bars 13 and rearwardly of the wall 14 is the heating chamber, the top of which is usually curved rearwardly and the bottom 17 of which slopes downwardly from the wall 14 toward the foundation, the curved top and sloping bottom finally forming a restricted opening for the discharge of the waste heat into the conduit to the stack. The portions of the furnace rearwardly of the wall 14 form no part of my invention, hence I do not illustrate them.

At a suitable point in wall 15 an opening 18 is provided into which is fitted one end of the pipe 19, the other end of the pipe being closely fitted into an opening provided in a vertical wall 20 which is spaced a suitable distance forwardly of wall 15. An arch 21 connects the two walls 15 and 20 at the top, a stack 22 being connected to the top of the arch and having a suitable check 22^a arranged in it for controlling the escape of gases from the chamber 23 formed by the said two walls and arch. Grate bars 24 are removably arranged in the bottom of chamber 23 and one or more layers of brick 25 are arranged on the bars. A suitable number of apertures 26 are provided in wall 15 in its upper portion and prefer-

ably on opposite sides of opening 18. The purpose of these openings is to permit the heat within chamber 10 to radiate and reflect into chamber 23.

5 Within chamber 23 is arranged a plurality of pipes 27, 28, 29 which project through the opposite side walls of the chamber and are connected successively exteriorly of the said walls by unions 30, so that they provide a 10 continuous conduit for the passage of air through the chamber 23, the air entering through pipe 27 and passing through the several pipes and finally passing through union 31, pipe 32, pipe 33 and union 34 into 15 pipe 19, from which it is discharged into chamber 10 along with the powdered coal which is blasted through nozzle 36. A suitable gate valve 35 may be arranged in pipe 32 for controlling the supply of warm air 20 to chamber 10.

If it is desired pipes 37 and 38 may be placed in the coke breeze 16, the opposite ends of the pipes projecting through the side walls of the furnace. Two of said ends are 25 connected by pipe 39, the other end of pipe 38 being connected by suitable unions to the free end of pipe 27 and a blower being connected to the free end of pipe 37. Or pipes 37 and 38 may be omitted and the blower 30 connected to the free end of pipe 27. The heat within the breeze 16 and that within chamber 23 and the heat thereof which has been transmitted through the wall itself, will cause the several pipes to become hot 35 and consequently warm the air as it passes through them. If pipes 37 and 38 are omitted the pipes within chamber 23 will then furnish the desired heated air.

Doors 39^a are provided in the front wall of 40 chamber 23 which furnish access to that chamber.

Nozzle 36 is connected at one end to a fuel supply pipe 40, the connection being somewhat loose so that the nozzle may be moved 45 upon the pipe 40 as a pivot to change the direction of its longitudinal axis so that the direction of the discharge of the fuel may be controlled as desired. To enable the nozzle to be readily adjusted I provide a lever 41 which is pivotally mounted upon a support 42 which support is movably secured to the bottom of pipe 19 by a bolt 43 which is threaded through the said bottom. One end of the lever 41 is bifurcated or provided 50 with a clevis 44 in which rests the forward end of the nozzle. A bracket 45 bent in the form of a right angle is secured to the rear end of lever 41 and each arm of the bracket is slotted or bifurcated and two adjustable 55 bolts 46 and 47 are threaded through the wall of pipe 19, the inner ends of the bolts having annular recesses in their peripheries in which recesses the bifurcated arms of bracket 45 engage. It is apparent that the 60 nozzle may be tilted in a vertical plane by

rotating bolt 46 and in a horizontal plane by rotating bolt 47, the rotation of which will move the bracket and the lever in the proper direction to cause the nozzle to swing in the desired direction.

70 It is apparent that the air heating pipes are accessible at all times for cleaning or repair without disturbing the furnace proper and that it will not interfere in the least with any part of the furnace or its operation, nor with making use of the waste heat of the furnace.

75 It is also apparent that by providing the stack 22 for chamber 23 the heat of the combustion chamber 10 may be more readily conducted into chamber 23 in starting the furnace, but the damper in said stack will be closed more or less in normal operation of the furnace, in order that the heated gases shall not be wasted. The stack also greatly 80 reduces the fuel consumption in initially heating up the furnace, since, in starting up, the damper in the main stack will be closed and that in stack 22 will be opened thereby compelling the gases of the combustion chamber to pass out through stack 22 and very quickly heating up the air conduits in 85 chamber 23 so that warm air is supplied almost immediately after starting up the furnace.

90 95 What I claim is:

1. The combination of a combustion chamber having communication at one end with a stack, a perforated vertical wall at the opposite end of the combustion chamber, a second vertical wall forwardly of the perforated wall and exteriorly of the combustion chamber, a conduit between the two vertical walls and adapted to be heated by reflected heat from the combustion chamber 100 and a discharge pipe communicating with the combustion chamber and having connection with the conduit, the conduit also having communication with outside air.

105 110 115 120 125 2. The combination of a combustion chamber having communication at one end with a stack, a perforated vertical wall at the opposite end of the combustion chamber, a discharge pipe supported in the wall and communicating with the combustion chamber, a vertical wall forwardly of the perforated wall, walls connecting the two vertical walls to form a chamber therebetween, and exterior of the combustion chamber, a conduit within the latter chamber 115 having communication with outside air and having connection with the discharge pipe, the perforated wall being adapted to admit reflected heat and hot gases from the combustion chamber into the conduit chamber 120 for heating the conduit and means in the discharge pipe for admitting fuel to the combustion chamber.

130 3. The combination of a combustion chamber having communication at one end

with a stack, a perforated vertical wall at the opposite end of the combustion chamber, a discharge pipe supported in the wall and communicating with the combustion chamber, a vertical wall forwardly of the perforated wall, walls connecting the two vertical walls to form a chamber therebetween and exterior of the combustion chamber, a stack connected to one of the walls of the latter chamber, a damper in the stack, a conduit within the latter chamber having communication with outside air and having connection with the discharge pipe, the perforated wall being adapted to admit reflected heat and hot gases from the combustion chamber into the conduit chamber for heating the conduit and means in the discharge pipe for admitting fuel to the combustion chamber.

5. In a furnace the combination with a

combustion chamber, a coke breeze in the 20 bottom of the combustion chamber, a conduit for outside air under pressure extending through the breeze and projecting exteriorly of the furnace, a second chamber adjacent the combustion chamber and having communication therewith and adapted to be heated thereby, a discharge pipe for air having communication with the combustion chamber, a conduit within the second chamber having connection with the first 25 30 mentioned conduit and the discharge pipe, and a nozzle within the discharge pipe for the discharge of fuel into the combustion chamber.

In witness whereof I hereunto subscribe 35 my name this 20th day of April, 1915.

JOSEPH McKENNA.
